UNITED STATES PATENT OFFICE.

ANTON BECKER, OF CHICAGO, ILLINOIS, ASSIGNOR TO JOSEPH S.
RALSTON, OF CHICAGO, ILLINOIS.

CAR-UNDERFRAME CONSTRUCTION.

No. 807,995.

Specification of Letters Patent.

Patented Dec. 19, 1905.

Application filed August 9, 1905. Serial No. 273,412.

To all whom it may concern:

Be it known that I, ANTON BECKER, a citizen of the United States, residing at Chicago, in the county of Cook and State of Illinois, have invented a certain new and useful Improvement in Car-Underframe Construction, of which the following is a specification.

My invention relates to the construction of the underframes for cars, and particularly to such an underframe made of metal which can be readily applied to wooden cars for the purpose of repairing and rebuilding the same.

The object of my invention is to provide such a mechanism which can be easily and cheaply made and installed in place under a car-body, which will be strong, and not readily liable to get out of order.

It consists in the use of a central girder running lengthwise of the car of greater height than the cross-bearers attached to it, the top plate of each cross-bearer extending from side to side of the car through slots cut in the webs of the I-beams or channel-irons forming the vertical members of the central girder, this in combination with the sills of the car and mechanism for securing the whole together.

It also consists in details of construction which will be hereinafter more fully described and claimed.

In the drawings, Figure 1 is a central sectional side view through a car having the device of my invention applied thereto. Fig. 2 is a plan view of Fig. 1, the floor-boards of the car being removed. Fig. 3 is a sectional detail view looking lengthwise of the car, taken through a cross-bearer of the car on the line 3 of Fig. 2. Figs. 4, 5, and 6 show the parts of Fig. 3 taken apart. Fig. 7 is a partial view of the side of the central girder where the cross-bearer goes through it, taken on line 7 of Fig. 3. Fig. 8 is a detail view of the inside of one plate of the girder, showing the slot through which the upper plate of the cross-bearer passes. Fig. 9 is a detail view looking at the side of the central girder, showing the method of applying the device of my invention to the bolster of an ordinary car. Fig. 10 is a detail of the central girder at the point of application of the bolster to the car. Fig. 11 is a side, Fig. 12 a plan, and Fig. 13

an end detail view, showing the method of applying the end sill to the bolster.

When an ordinary freight-car is wrecked or otherwise out of repair, it very frequently happens that the truss-rods supporting the underframe of the car are injured, and it is then desirable to be able to repair the car without replacing these truss-rods. It is also desirable to build cars in the first instance without such truss-rods, and by the device of my invention I provide means by which this can be done, using either in a new or old car the wooden sills of an ordinary car or the entire car-body.

Referring to the drawings, the numerals 15 indicate the sills of an ordinary car, having across their tops floor-boards 16. These parts may be the floor of a flat, a gondola, a box, or a stock car without departing from my invention. To these sills I apply the underframe of my invention, consisting of a metallic center girder and cross-bearers. The central girder is made, preferably, in box form of channel-irons 20 or corresponding I-beams, 75 joined together at top and bottom by plates 21 and 22. This girder is, as shown, preferably made of considerable height, so that it will occupy approximately the depth of the sills 15 and extend a considerable distance below them. Through this box-girder I cut slots 23, through which are placed the top plates 25 of cross-bearers extending intermediate between the bolsters from side to side of the car, as shown. Below these plates 25 and on opposite sides of the central girder are cast-iron fillers 26, made triangular in form, the apexes of the triangles extending toward the side of the car, as shown. Below these fillers and extending from side to side of the car is the lower plate 28 of the cross-bearers. Extending vertically through the sills 15 and the upper and lower plates and the fillers just described are vertical bolts 30, thus fastening the complete cross-bearers to the sills and parts attached thereto, as shown. The lower under plates 28 of the cross-bearers are attached to the flanges 31 of the channels 20 and the lower plate 22 of the central girder by bolts or rivets 32, as shown. The upper plates 25 of the cross-bearers are secured to the lower plates of the cross-bearer outside the fillers 26 by the bolts

or rivets 34. Extending from the ends of the cross-bearers are clips 35, adapted to support the side sills 36 of the car, being secured thereto by bolts or pins 37, as shown.

- 5 For repair purposes I make the central girder and the parts of the cross-bearers in separate pieces and when a car has to be repaired quickly have a carpenter prepare the sills of the old car for the reception of my 10 underframe by boring suitable holes for the bolts 30 through the sills. I then have a force of men place the plates 25 through the slots 23 in the central girder and after this is done attach the fillers 26 and lower plates 28 and 15 secure the bolts 30 in position. By this construction I am able to use a relatively deep metal central girder, which gives the car great strength and does away with the necessity of using truss-rods, while permitting a relatively 20 low cross-bearer to be used.

In order to apply the device of my invention to the bolsters 40 of old cars, I cut into the channel-irons 20 or other forms of sides of the central girder at the point at which the 25 bolster is applied inverted-U-shaped notches 41, in which the bolster 40 is adapted to fit, as shown in Fig. 9. I reinforce the bolster at the point of cut by applying plates 43, secured to the bolster by bolts or rivets 44, as shown. 30 Across the under side of the bolster 40 I secure to the central girder a plate 46, the plate being secured to the lower flanges 31 and the lower plate 22 of the girder by bolts or rivets 47, as shown. By this construction I am able to 35 quickly apply the underframe of my construction to the old bolster of the car, thereby repairing the car and saving the expense of providing a new bolster in the underframe.

I secure the central bolster to the end sills 40 by the novel means shown in Figs. 11, 12, and 13, consisting in slitting down the channel-irons 20 in the vertical lines 50 a distance from the ends of the car equal to the width of the end sills 51 and making the shear of a 45 depth equal to the depth of the end sills, thus forming a lip or wing 52 on each channel-iron. I bend these wings 52 out at right angles to the web of the channel-iron, so as to form shelves, as shown in Fig. 13, on which the 50 end sills rest. I secure the end sills 51 to the lips or wings 52 by the vertical bolts 54, as shown. In order to strengthen the structure just described, I secure the angle-irons 55 to the channel-irons 20 by rivets 56 and to the 55 end sills 51 by the horizontal bolts 57, as shown.

Having thus described my invention, what I claim as new, and desire to secure by Letters Patent, is—

- 60 1. In a car, an underframe composed of a plurality of sills extending lengthwise of the car, a central girder of greater height than the sills, having part of its height extending

above the bottoms of the sills and part of its height extending below the bottoms of said 65 sills, a plurality of cross-bearers composed of separate top and bottom plates with intermediate fillers extending crosswise of the car, the top plates of the cross-bearers being adjacent to the bottoms of the sills and extending across 70 the car through slots cut in the central girder, the bottom plates of the cross-bearers extending across the bottom of the girder and the fillers being located at each side of the girder between the top and bottom plates; and means 75 engaging the sills and the bottom plates of the cross-bearers for securing the whole together.

2. In a car an underframe composed of a plurality of sills extending lengthwise of the car, a central girder of greater height than 80 the sills, having part of its height extending above the bottoms of the sills and part of its height extending below the bottoms of said sills, a plurality of cross-bearers composed of top and bottom plates extending from side to 85 side of the car and triangular fillers between said top and bottom plates, the top plates of said cross-bearers being adjacent to the bottoms of the sills and extending across the car through slots cut in the central girder and the 90 bottom plates of the cross-bearers extending across the bottom of the girders and a plurality of bolts extending through said sills, top and bottom plates and fillers of the cross-bearers to secure the whole together substantially as described. 95

3. In a car an underframe composed of a plurality of sills extending lengthwise of the car intermediate between two side sills of greater depth than said first-mentioned sills 100 also extending lengthwise of the car; a central girder of greater height than said intermediate sills having part of its height extending above the bottoms of the sills and part of its height extending below the bottoms of 105 said sills, a plurality of cross-bearers composed of top plates extending across the car adjacent to the bottoms of the intermediate sills, triangular fillers below said top plate as described, and a bottom plate extending crosswise of the car across the bottom of said central girder and along the bottoms of said fillers; means upon the ends of said cross-bearers for securing them to the side sills and a plurality 110 of bolts through said first-mentioned sills the top and bottom plates and fillers of said cross-bearers whereby the whole may be detachably secured together as described. 115

4. In a car the combination of a central plate-girder having an inverted - U - shaped 120 notch 41 extending upward from the bottom of said girder said notch being of the same depth as the height of the bolster which is to be inserted therein, a reinforcing plate or plates 43 secured to said girder adjacent to 125 said notch, a bolster inserted crosswise of the

car in said U-shaped notch and unsecured to said girder; and a flat plate extending along the bottom of said girder secured to the girder proper and to said bolster.

5. In a car, the combination of a longitudinal girder made of metal plates or channel-irons, a shelf on the side of said girder formed by slitting down a portion of the plate and bending the slitted portion to a position at 10 right angles to the plane of the main plate or

channel and an end sill mounted crosswise of the girder on said shelf and secured thereto.

In witness whereof I have hereunto subscribed my name in the presence of two witnesses.

ANTON BECKER.
